UNITED STATES PATENT OFFICE.

HUGH DAVIS, OF MELVIN, MICHIGAN.

RAIL-JOINT.

1,189,069.

Specification of Letters Patent. Patented June 27, 1916.

Application filed April 17, 1916. Serial No. 91,690.

To all whom it may concern:

Be it known that I, HUGH DAVIS, a citizen of the United States, residing at Melvin, in the county of Sanilac and State of Michigan, have invented new and useful Improvements in Rail-Joints, of which the following is a specification.

This invention relates to means for connecting the meeting ends of two rails.

10 The primary object of the invention is to provide the meeting ends of railway rails with interengaging members which are adapted to guide the rails into proper alignment and when the rails are associated, tend 15 to prevent the lateral or sinking movement thereof, but permitting of a limited longitudinal movement incident to the expansion and contraction of the rails and also to hold the rails in proper registering alignment.

20 With the above and other objects in view the improvement resides in the construction, combination and arrangement of parts set forth in the following specification and falling within the scope of the appended claims.

25 In the drawings: Figure 1 is a perspective view of two rails constructed and connected in accordance with the present invention, Fig. 2 is a horizontal sectional view taken approximately in a line with the connecting members for the rails, Fig. 3 is a transverse sectional view approximately on the line 3—3 of Fig. 2, Fig. 4 is a side elevation of the connected rails, the chair member being dispensed with, Fig. 5 is a perspective view of one of the rail ends, Fig. 6 is a similar view of the co-acting rail end, Fig. 7 is a top plan view illustrating a modification of two connected rails, Fig. 8 is a perspective view of one of the rail ends, 40 and Fig. 9 is a similar view of the other or co-acting rail end.

In the drawings, 10 and 11 designate two rails which rest upon and are secured to the ordinary ties 12. The rails have their body 45 portions of the ordinary construction, each including a head, a web and a base flange, but if desired the webs may be thickened at the ends of the rails. The rail 10 has both its head and its base extending beyond its 50 web, and the end of its web formed with a vertically disposed substantially V-shaped pocket 13, and its base flange cut angularly from one of its edges to the other, as indicated by the numeral 14. The head at the 55 upper portion or tread surface thereof is also cut angularly, in the direction of the

angular end 14 of the base flange, providing the said head with a tongue 15, and the said head is cut horizontally and vertically at an angle opposite to that of the inner 60 angular wall of the tongue 15 providing the said end of the rail with a lower tongue 16. The angular cuts upon what I will term the inner walls of both the tongues 15 and 16 start from diagonally opposite points on the 65 sides of the head, as clearly illustrated in the drawings. The second rail 11 has its web projecting beyond its base flange and the end of the said web pointed or V-shaped in plan, as indicated by the numeral 17, and 70 this V-shaped end is adapted to be snugly received in the V-shaped pocket of the web of the rail 10, when the rail ends are associated. The base flange of the rail 11 is cut angularly, as at 18, and this angular end of 75 the said flange is adapted to abut with the angular end 14 of the base of the rail 10, when the rails are connected. The head of the rail 11 terminates approximately in a line with the pointed end of the web 17 80 thereof and the head, from the upper surface or tread thereof is cut vertically at an angle providing the said tread portion of the head at the end of the rail with a tongue 19. The head of the rail, approximately 85 centrally thereof, is cut horizontally, while the lower portion of the head is cut vertically in an angular direction providing a lower tongue 20, and the inner or angular wall of the said lower tongue is disposed at 90 an opposite angle to the inner or angular wall of the upper tongue 19. The said angular wall of the lower tongue underlies the lower horizontally straight wall of the upper tongue for a considerable distance and 95 the said wall of the said lower tongue also projects over the extending web so that the said web provides a horizontally straight shoulder 21 which is disposed below the upper tongue 19. The angular walls of the 100 upper tongues 15 and 19 as well as the angular walls of the lower tongues 16 and 20 are adapted to abut when the rail ends are assembled, and the shoulder 21 provides a rest for the lower tongue 16 of the rail 10. 105

By a construction as above described it will be noted that the beveled or angular faces on the ends of the co-acting rails when brought into contacting relation with each other will serve as means for properly 110 guiding the rails in a position to be connected and the interlocking engagement is

such as to prevent the vertical or sinking movement of the rails at the joint thereof as well as any lateral movement of the said rails.

5 Preferably I connect the ends of the rails 10 and 11 by a chair member 22 that includes a flat base 23 upon which the rails rest and which is provided with angular side members 24 having their inner surfaces shaped to engage with the sides of the webs, the base flanges and to underlie the heads of the rails. The side members 24 of the chair have openings which register with elongated openings in the webs of the rails 15 and passing through these openings are the usual connecting bolts that are provided with the ordinary securing nuts. The chair may be spiked to ties in the ordinary manner.

20 In Figs. 7 to 9 the webs and base flanges of the rails 25 and 26 have their ends constructed substantially similar to that just described, but the head of the rail 25 is formed at its end with a longitudinally disposed V-shaped slot or depression 27 which is closed for the major portion of its length by the upper and horizontally straight wall or shoulder 28 provided by the upper surface of the web of the said rail 25. The 25 other rail 26 has its head formed with a longitudinally extending substantially V-shaped tongue 29 which is adapted to be received in the V-shaped slot or depression 27 of the rail 25, and the underface of the said tongue is adapted to rest upon the shoulder 28. The end of the head of the rail 26 at the inner terminal of its tongue 29 is formed with vertical notches 30 to receive the shoulders at the end of the head of the 30 rail 25 outward of the angularly disposed vertical walls providing the slot or depression 27, as clearly shown in the drawings.

It is to be understood that a chair member similar to that previously described may 45 be employed in connection with these rails, and also that the webs of the rails are connected to the said chair in the usual manner.

From the above description, taken in connection with the accompanying drawings, the simplicity of the device, as well as the

advantages thereof will, it is thought, be perfectly apparent to those skilled in the art to which such invention appertains without further detailed description.

55

Having thus described the invention, what I claim is:

1. The herein described construction of means for connecting the meeting ends of rails including two rails, one having its base and head projecting beyond its web and the said web formed with a vertically disposed V-shaped pocket, the base flange terminating in an angular shoulder, the projecting head being cut to provide an angular tongue, the second rail having its web extending beyond its base, and the end of the web V-shaped in plan to be received in the V-shaped pocket of the first mentioned rail, the base flange of the said second mentioned rail being cut angularly to contact with the angular base flange of the first mentioned rail and the head of the rail being cut angularly over the web thereof to provide a tongue which engages with the tongue of the first mentioned rail and the said tongue of the first mentioned rail adapted to rest upon the upper surface of the web of the second mentioned rail, and means for connecting the rail ends.

60

2. In a rail joint, two rails, one of said rails having its web at its end formed with a vertically disposed V-shaped pocket, its head cut at different angles to provide the same with an upper and a lower tongue, the second rail having the end of its web V-shaped in plan to be received in the pocket of the first mentioned rail and having its head cut angularly in opposite directions to provide upper and lower tongues, the web of the said second mentioned rail being extended below the upper tongue of the said rail, and the angular faces of the tongues of both the rails adapted to engage when the rails are assembled, and the lower tongue of the first mentioned rail adapted to be supported upon the upper surface of the web of the second mentioned rail, and means for connecting the rail ends.

65

In testimony whereof I affix my signature.

HUGH DAVIS.
